SHAVING KIT

Glen A. Blanton, Albemarle, N. C.

Application April 7, 1941, Serial No. 387,341

3 Claims. (Cl. 240—2)

The present invention relates to new and useful improvements in shaving kits, and has for its primary object to provide a receptacle having a plug-in socket for an electric razor or an electric fan having electric connection with a source of current and also mounting a fluorescent lamp in the receptacle which is also connected in the electric circuit and carried by a swingable front panel in the receptacle to illuminate the face of the person while shaving.

A further object is to provide a foldable mirror mounted in the receptacle and adapted for swinging movement above the lamp into a desired position.

A still further object is to provide a device of this character of simple and practical construction, which is neat and attractive in appearance, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which—

Figure 1 is a top plan view with the kit shown in open position,

Figure 2 is a front elevational view,

Figure 3 is a transverse sectional view, and

Figure 4 is a perspective view of the kit in its closed position.

Referring now to the drawings in detail, wherein for the purpose of illustration I have disclosed a preferred embodiment of the invention, the numeral 5 designates a box-like container or receptacle generally which includes a bottom 6, end walls 7, a back 8 and a hinged cover 9 hingedly connected as at 10 to the back for swinging over the open top of the receptacle.

The front wall 11 of the receptacle is hinged as at 12 at its lower edge for swinging into and out of position for closing the front of the receptacle. Mounted in the receptacle adjacent the front thereof is a supporting structure 13 including a vertical panel 14 and a horizontal shelf 15 projecting forwardly from the panel, the vertical panel having a plurality of plug-in sockets 16 attached thereto as well as toggle switches 17 for controlling an electric circuit having a feed wire 18 leading to a suitable source of current, the feed wire being connected to the plug-in socket 16 and to the switches 17 in a conventional manner such as shown in Figure 1 of the drawings.

Secured to the inside of the front wall or panel 11 adjacent each end thereof, is a pair of brackets 19 having terminals 20 attached thereto for the ends of a tubular fluorescent lamp 21 of conventional construction, the terminals 20 also being electrically connected with the circuit wire. The lamp 21 is thus supported in a parallel relation with respect to the inner surface of the front panel 11.

10 The ends of the front panel 11 are bent inwardly as shown at 22 to form wings which may be of substantially triangular shape as shown to advantage in Figure 3 of the drawings, two edges of the wings being free and projecting inwardly of the receptacle in frictional engagement with the end walls 7 whereby to secure the front panel 11 in a desired outwardly inclined position.

A mirror supporting plate 23 is provided with 20 trunnions 24 projecting outwardly from opposite sides at one edge and which are rotatably supported in U-shaped clamp devices 25 secured by bolts 26 to the shelf 15. Also secured to a relative opposite edge of the support 23 are a pair 25 of U-shaped clamping devices 27 by means of bolts 28, the clamping devices 27 having the ends of a rod 29 rotatably supported therein. A pair of lugs 30 are secured to the rod 29, one end of the lugs being welded or otherwise secured to the 30 back 31 of the mirror 32, the lugs being secured adjacent one edge of the mirror whereby to permit the mirror to swing by the rotary movement of the rod in the clamps 27. The tightening of the bolts 26 will serve to bind the trunnions 24 in the clamp devices 25 for the purpose of securing the support 23 in a desired inclined position and likewise the tightening of the bolts 28 will serve to secure the mirror in an inclined position on the support.

40 The compartment behind the chassis provides space for packing the electric razor or other shaving equipment in the cabinet.

It is believed the details of construction and manner of use of the device will be readily understood from the foregoing without further detailed explanation.

What I claim is:

1. A shaving kit comprising a cabinet having a front wall hinged at its lower edge, a vertical 50 and a horizontal partition in the cabinet and cooperating with said front wall to form a compartment in the front portion of the cabinet, a lamp supported on the inside of said front wall and adapted to illuminate the face of a person 55 in front of the cabinet when the wall is swung

outwardly, means for supporting the front wall in an outwardly inclined position, and a mirror adjustably supported on the horizontal partition above the lamp, said lamp being movable into a position within the compartment and said mirror being foldable upon the horizontal partition when not in use.

2. A shaving kit comprising a cabinet having a front wall hinged at its lower edge, a vertical and a horizontal partition in the cabinet and co-operating with said front wall to form a compartment in the front portion of the cabinet, a lamp supported on the inside of said front wall and adapted to illuminate the face of a person in front of the cabinet when the wall is swung outwardly, inwardly projecting wings on the ends of said front wall having frictional engagement with the cabinet to secure the front wall in outwardly inclined position, and a mirror adjustably supported on the horizontal partition above the lamp, said lamp being movable into a position within the compartment and said mirror being

foldable upon the horizontal partition when not in use.

3. A shaving kit comprising a cabinet having a front wall hinged at its lower edge, a vertical and a horizontal partition in the cabinet and cooperating with said front wall to form a compartment in the front portion of the cabinet, a lamp supported on the inside of said front wall and adapted to illuminate the face of a person in front of the cabinet when the wall is swung outwardly, means for supporting the front wall in an outwardly inclined position, a mirror support pivoted at one edge to the horizontal partition and a mirror pivoted at one edge to a relatively opposite edge of the support for adjustably swinging the mirror vertically and forwardly relative to the lamp, said lamp being movable into a position within the compartment and said mirror and mirror support being foldable upon the horizontal partition when not in use.

GLEN A. BLANTON.
